UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

TELEPHONE CIRCUITS.

Application filed April 3, 1924. Serial No. 703,895.

This invention relates to telephone circuits and more particularly to the circuits of a telephone set including a receiver and a transmitter.

5 It is an object of the present invention to provide circuit arrangements which will deliver the maximum amount of energy in the form of an outgoing signal to a telephone line and which will receive the maximum, 10 amount of energy in the form of an incoming signal from said telephone line without the disturbance of the receiving circuit by the transmission circuit, which disturbance is commonly known as "side-tone" in the 15 receiver. In other words it is the object of the invention to provide a circuit arrangement for preventing talking currents from the talking net-work from interfering seriously with the receiving net-work.

20 In the embodiment of the invention herein described well-known substation equipment such as a receiver and a signal or ringer, are associated in a circuit net-work with a two-element transmitter and an induction coil having a secondary winding which is tapped at an intermediate point.

In the drawings Fig. 1 diagrammatically represents the invention applied to the substation circuits of a manual telephone line. 30 Fig. 2 shows a similar substation circuit arrangement in which an impulse transmitter with a make-break type of shunt spring combination is provided. Fig. 3 shows a substation circuit arrangement provided 35 with an impulse sender similar to that shown in Fig. 2, except that the shunt spring combination includes three normally open contact springs.

The transmitter herein referred to as a 40 differential microphone, may consist of a diaphragm, on each side of which a carbon button impinges. Other types of transmitters such as electromagnetic or electrostatic transmitters may be employed.

45 The impulse transmitter or sender herein referred to, may be similar in construction to that disclosed on pages 34 and 35 of Automatic Telephony, by Smith and Campbell, first edition but in which the shunt spring combinations are differently arranged.

50 Referring to Fig. 1, 5 designates the well known type of receiver associated with a differential microphone, which consists of a diaphragm 6 on either side of which carbon

buttons 7 and 11 impinge. The primary 55 winding of an induction coil is indicated at 8, while the secondary winding of this induction coil is tapped at its mid-point to form windings 9 and 10 which are oppositely wound. It will be seen that the ringer 13 is bridged across the line conductors 14 and 15 in series with the condenser 12. The receiver 5 when removed from the switchhook closes contacts 32 and 33 in the well known manner and thereby completes a circuit for the receiver 5 by which incoming currents pass over the line conductor 15, primary winding 8 of the induction coil, hookswitch contacts 32 and 33, receiver 5 through the condenser 12 and thence to the line conductor 14. The two electrodes 7 and 11 of the transmitter with the secondary windings 9 and 10, of the induction coil are included in shunt of the circuit including the receiver 5 and the condenser 12. This 75 shunt can be so designed that it offers high impedance to the incoming signals, thereby forcing them through the receiver 5, which with the condenser 12 in the series circuit can be so proportioned as to offer low impedance to the mentioned incoming signals.

When this net-work is used to transmit outgoing currents, such currents do not produce serious side-tone noises in the receiver 5. Let it be assumed that at some instant 85 the button 7 is being compressed and the button 11 is being expanded. The resistance of the button 7 is therefore decreased, while the resistance of the button 11 is increasing to cause an increasing flow of current 90 through the secondary winding 9 and a reduced flow of current through the secondary winding 10. If the current over the conductors 14 and 15 is in the direction shown by the full line arrow and if an increase of current through the winding 9 induces current in primary winding 8 in the direction shown by the dotted arrow, the decrease in current flowing through secondary winding 10, at this time causes a further increased 100 flow of current through the primary winding 8 as shown by the heavy dotted arrow. This is due to the fact that the secondary windings 9 and 10 are oppositely wound.

If at a certain other instant, button 11 105 is being compressed and button 7 is being expanded, the effect is opposite to that described under the previous condition, since

a decrease of current flow through winding 9 and an increase of current flow through winding 10 induces a current in winding 8 in opposition to the line current to reduce 5 the current flow over the telephone line. Since these increases and decreases of current flow pass through the transmitter buttons 7 and 11 instead of being impressed across the receiver, the side-tone action 10 through the receiver 5 is reduced.

Referring to Fig. 2 the net-work of Fig. 1 has been modified to incorporate a well known type of impulse sender, also known as a "dial," which is equipped with the 15 make-break type of shunt spring combination. The transmitting circuit of Fig. 2 differs from that described in Fig. 1 by the inclusion of the impulse springs 16, but the circuit of the receiver 5 during the reception 20 of signals is the same as the net-work of Fig. 1. The normally closed contacts 17 of the shunt spring combination, however, are opened by the operation of the impulse sender, in order that disagreeable clicks may 25 not be heard in the receiver 5 during the transmission of impulses. The normally opened contacts 18 are closed during the operation of the impulse sender so that during the sending of impulses the impedance 30 of the differential microphone is not included in the signaling circuit extending through the line conductors 14 and 15.

In the modified form of the invention shown in Fig. 3, the circuit arrangement 35 differs from Fig. 1 by reason of the fact that an impulse sender provided with a shunt spring combination having three normally open contacts, is used and a different hookswitch spring combination is employed. In 40 this arrangement it will be noted that the receiver 5, as well as the differential microphone are shunted when the dial is operated to close the shunt springs 19, 20 and 21. In 45 this instance also the impulse springs 16 are serially included in the telephone line represented by the conductors 14 and 15.

What I claim is:

1. In a telephone net-work, a pair of line 50 conductors, a bridge across said conductors, a differential microphone having its elements connected in multiple in said bridge, a receiver connected in shunt of a portion of said bridge, and an impulse sender having 55 impulse springs in said bridge and off normal springs for controlling said receiver connection.

2. In a telephone net-work, a pair of line 60 conductors, a bridge across said conductors, a transmitter comprising a diaphragm and 65 a button engaging each side of said diaphragm, the buttons of said transmitter being connected in multiple in said bridge, a receiver connected in shunt of a portion of 70 said bridge, and an impulse sender having impulse springs in said bridge and off 75

normal springs for controlling said receiver connection.

3. In a telephone net-work, a pair of line 80 conductors, a bridge across said conductors, a differential microphone having its elements connected in multiple in said bridge, a circuit in shunt of a portion of said bridge, a receiver and a condenser in series in said shunt circuit, and a circuit normally closed 85 across said conductors including a ringer and said condenser in series.

4. In a telephone net-work, a pair of line 90 conductors, a bridge across said conductors, a differential microphone telephonically connected in said bridge, a receiver and a ringer telephonically related to said line conductors and said bridge by conductors, and a condenser common to said conductors.

5. In a telephone net-work, a pair of line 95 conductors, a bridge across said conductors, a differential microphone having its elements connected in multiple in said bridge, a circuit in shunt of said bridge, a receiver in said shunt circuit, a hookswitch for normally opening said bridge and said shunt circuit, and an impulse sender having impulse springs in said bridge and other springs to complete a by-path about said transmitter during the operation of said 100 impulse sender.

6. In a telephone net-work, a pair of line 105 conductors, a bridge across said conductors, a differential microphone having its elements connected in multiple in said bridge, a circuit in shunt of said bridge, a receiver in 110 said shunt circuit, a hookswitch for normally opening said bridge and said shunt circuit, a ringer normally connected in a conductor across said line conductors, and a condenser common to said shunt circuit and 115 to said ringer conductor.

7. In a telephone net-work, a pair of line 120 conductors, a bridge including a differential microphone connected across said line conductors, a second bridge including a ringer and a condenser connected across said line 125 conductors, and a third bridge including a receiver connected to points on said first two bridges.

8. In a telephone net-work, a pair of line 130 conductors, a bridge including a differential microphone connected across said line conductors, a second bridge including a ringer and a condenser connected across said line 135 conductors, and a third bridge including a receiver connected to points on said first bridges, and a hookswitch for opening said first and third bridges.

9. In a telephone net-work, a pair of line 140 conductors, a bridge connected across said line conductors, said bridge including the primary winding of an induction coil in series with two portions in multiple of the secondary winding of said induction coil, a transmitter having an element in series with 145

each portion of said secondary winding, and a receiver and a ringer electrically associated with said bridge and line conductors.

10. In a telephone net-work, a pair of line conductors, a transmitter comprising a diaphragm and a transmitter button engaging each side of said diaphragm, an induction coil including a primary coil and a secondary coil, said secondary coil having two portions which are substantially equal, oppositely wound and connected with respect to each other, a bridge across said line conductors, said bridge including said transmitter buttons and the portions of said secondary coil in multiple but in series with said diaphragm and said primary coil, and a receiver associated with said line conductors.

11. In a telephone net-work, a pair of line conductors, a three-electrode transmitter, an induction coil including a primary winding and a secondary winding, said secondary winding having two portions which are substantially equal, oppositely wound and connected with respect to each other, a bridge across said line conductors, said bridge including certain of said transmitter electrodes and the portions of said secondary winding in multiple but in series with said primary

winding, and a receiver associated with said line conductors.

12. The method of reducing side-tone in a telephone substation circuit which comprises generating by means of a differential microphone, currents through substantially equal and oppositely wound secondary windings of an induction coil, the primary of which is included in the receiver and line circuits in series.

13. The method of reducing side-tone in a telephone substation circuit which comprises generating currents through substantially equal and oppositely wound secondary windings of an induction coil, the primary of which is included in the receiver and line circuits in series.

14. The method of reducing side-tone in a telephone substation circuit which comprises generating by means of a differential microphone, currents through two substantially equal and oppositely wound windings of an induction coil, a third winding of said induction coil being included in the receiver and line circuits in series.

In witness whereof, I hereunto subscribe my name this 1st day of April, A. D. 1924.

WINFRED T. POWELL.
